LINING AND BEVELING MACHINE

Vernon E. Royle, Paterson, N. J.

Application February 5, 1937, Serial No. 124,257

7 Claims. (Cl. 90—58)

This invention relates to a lining and beveling machine, primarily designed for the use of photo-engravers, and has for an object to provide such a machine in which the carriage and table are offset laterally from the pedestal, and the outer longitudinal edges of the carriage and table are rigidly supported throughout the entire length of travel in both directions, thereby permitting the increase in speed of movement and minimizing the friction of the parts.

Another object consists in providing such a machine in which the support for the outer longitudinal edges of the carriage and table in their traveling movement includes a straight line parallel motion means connected to the pedestal and carriage and movable therewith, whereby greater accessibility of the work on the table is obtained.

Another object consists in providing certain improvements in the form, construction and arrangement of the several parts, whereby the above named and other objects may effectively be attained.

A practical embodiment of my invention is represented in the accompanying drawings, in which

Fig. 1 represents a side elevation of the machine;

Fig. 2 represents a front elevation of the same;

Fig. 3 represents a detail vertical section, taken in the plane of the line III—III of Fig. 1, looking in the direction of the arrows;

Figs. 4 to 7 inclusive represent detail vertical sections, on a larger scale, taken in the plane of the lines IV—IV, V—V, VI—VI, and VII—VII of Fig. 1 respectively, looking in the direction of the arrows; and

Figs. 8 to 10 inclusive represent diagrammatic views of the straight line parallel motion means with the carriage shown in different positions throughout its length of travel.

The machine includes a base 1, a pedestal 2 uprising therefrom, a carriage 3, one longitudinal side of which is supported by a V-shaped rail 4 secured to the side of the pedestal by bolts 5, and a table 6 for receiving the plate to be operated upon, which table is secured to the carriage 3 in any well known or approved manner, so that the carriage and table are reciprocated during the operation of the machine. The other or outer longitudinal side of the carriage 3 is supported by a straight line parallel means which comprises a series of links connected together and arranged to move about two centers of motion. The links 7, 8, 9 and 10 are substantially of equal length and are pivoted together by bolts

11, 12, 13 and 14, in the form of a rhombus. The pivot bolt 14 of the links 7 and 10 is also connected with the upper end of a link 15, while the upper end of a link 16 is connected with the links 8 and 9 by the pivot bolt 12. The links 15, 16 are substantially equal in length, and the lower ends of the links are connected by a pivot bolt 17 to oscillate in a bracket 18 carried by a plate 19, which is fixed to the side of the pedestal 2 by bolts 20. The pivot bolt 13 of the links 9 and 10 connects the upper end of a link 21, the lower end of which is pivoted on a stud bolt 22 fixed on the plate 19. The links 7, 8, together with their pivot bolt 11, are secured in a bracket 23 fixed by the bolts 24, 25 to depend centrally of the longitudinal edge of the carriage 3.

In order to minimize the friction of the pivoted joints of the links, I provide anti-friction bearings of which the upper end of the link 7 has a ball bearing 26, while the upper end of the link 8 is bifurcated at 27 (Fig. 4) and frictionally secured to the pivot bolt 11, which is journaled in ball bearings 28, 29 carried by the bracket 23. The lower end of the link 7 is bifurcated at 30 (Fig. 5) and frictionally secured to the pivot bolt 14 which is journaled in ball bearings 31, 32 carried by the upper end of the oscillating link 16. The upper end of the link 10 which is also pivoted on the bolt 14 is provided with ball bearings 33.

Anti-friction bearings associated with the pivot bolt 12 and its coaxing lower and upper ends of the links 8 and 9 respectively, and the upper end of the oscillating link 16, are similar to that shown and described with respect to the pivot bolt 14, links 7, 10 and 15, so that further description is therefore deemed unnecessary. The lower end of the oscillating link 15 is provided with a ball bearing 34 which coacts with the pivot bolt 17, while the lower end of the oscillating link 16 is bifurcated at 35 and frictionally secured to the pivot bolt 17. The pivot bolt 17 is journaled in ball bearings 36, 37 carried by the bracket 18, as shown in Fig. 7. The upper end of the oscillating link 21, which is connected with the lower end of the links 8, 10 by the pivot bolt 13, is also provided with ball bearings (not shown) similar to the ball bearing shown and described with respect to the links 7, 10 and 15, so that further description is deemed unnecessary. The lower end of the oscillating link 21 is provided with a ball bearing 38 which coacts with the pivot stud bolt 22 carried by the plate 19, as shown in Fig. 6.

As a result of the construction above described, it will be seen that the carriage is held in position and accurately guided by the rail 4, while the link means adequately support the other or outer longitudinal side of the carriage and permit its reciprocating movement with a minimum resistance.

The means for reciprocating the carriage 3 includes a hand wheel 39 which is fixed on a rod 40 that is journaled in a swinging bearing 41 which is carried by a bracket 42 fixed to the side of the carriage, as shown in Figs. 1 and 2. A screw bolt 43 serves as a pivot to permit the bearing 41 to swing in a vertical plane on the bracket 42. The rod 40 pierces the adjacent side of the carriage 3, as indicated at 44, and the inner end is furnished with a helical gear 45 that normally meshes with a rack 46 that is clamped by bolts 5 to the V-shaped rail 4 and hence is fixedly secured to the pedestal 2.

From the foregoing, it will be seen that turning the hand wheel 39 will slide the carriage on its rail 4, and the link motion, by virtue of the engagement of the helical gear 45 with the rack 46 and with the hand wheel 39 and the connected parts, will travel with the carriage 3 in its movement. This provides a very smooth and positive action because of the character of the intermeshing parts and the traveling movement with the table of the actuating gear 45 and connected elements. The helical gear, or the like, will always have at least two teeth in mesh with the rack because of the angularity of the teeth, which effects an even and precise movement; and such an arrangement also allows the shaft which operates the helical gear to be placed at an acute angle to the rack, whereby its operating hand wheel may be convenient to the operator of the machine without being in his way. Furthermore, a gear of the helical type tends to prevent chips from clogging the rack, because the engaging movement of the parts is such as to urge the chips out of the rack instead of to hold them therein and crush them.

When the carriage with the table thereon is reciprocated in the operation of the machine from one position to another, the link motion will assume different positions such as that shown diagrammatically in Figs. 8 to 10 inclusive, and the links will move in the direction of travel, as indicated by the several arrows. The actuation of the carriage 3 transmits its motion through the bracket 23 and its pivot bolt 11 to the links 7 and 8 which move the links 9 and 10 through the pivot bolts 12, 13 and 14. This movement of the links 7 to 10 inclusive and their pivot bolts 11 to 14 inclusive is transferred to the link 21 which is oscillated on its stud bolt 22 fast on the plate 19 which is fixed to the side of the pedestal 2. Simultaneously the links 15 and 16 will be oscillated on the pivot bolt 17 journaled in the bracket 18 on the plate 19 by their connections 14 and 12 of the links 7 to 10 inclusive. Thus it will be seen that, by the co-operation of the several links with their fixed and movable fulcrums, a straight line parallel motion will be produced, and by its connection between the carriage and pedestal, the outer longitudinal side of the carriage will be rigidly supported in any and all positions throughout its entire length of travel in both directions.

The cutter head for the beveling is denoted by 47 and is mounted on a spindle 48 journaled in bearings 49, 49 carried on top of the pedestal 2. The spindle is driven by means of a band

pulley 50 from a suitable source of power (not shown).

The clamp 51 for securing the work to the table is herein briefly stated as being capable of moving vertically toward and away from the work, the construction and operation of which is well understood by those skilled in the art.

The machine also includes a head for a variety of lining tools or the like, which is indicated generally by 52 (see Fig. 1). The construction and operation of this head for the lining tools is set forth in United States Patent No. 1,226,912, dated May 22, 1917, so that the same will not be detailed herein.

The operation of the various parts of the machine has been described in connection with setting forth their construction, so that it is not regarded as necessary here to re-state the operation of the machine as a whole.

It may, however, be noted that the construction and arrangement well adapts the machine for attaining the objects hereinabove outlined and others inherent in its construction, and that its design contemplates efficiency, accuracy and speed in operation, together with general adaptability for meeting varying needs of this particular class of work.

It will be understood that various changes may be resorted to in the form, construction and arrangement of the several parts without departing from the spirit and scope of my invention; and hence I do not intend to be limited to the details herein shown and described, except as they may be included in the claims.

What I claim is:

1. In a lining and beveling machine, a flat reciprocating work table offset laterally from the machine, manually operable means for moving the table, said means being mounted on the table, and a vertically disposed oscillating link 40 mechanism pivoted to said table and movable as a unit in a vertical plane for supporting the offset outer side of the table throughout its movement in a straight line.

2. In a lining and beveling machine, a flat reciprocating work table offset laterally from the machine, manually operable means for moving the table, said means being mounted on the table, and a vertically disposed oscillating mechanism comprising a series of interconnected links 50 pivoted to said table and movable as a unit in a vertical plane for supporting the offset outer side of the table throughout its movement in a straight line.

3. In a lining and beveling machine, a pedestal, a flat work table offset laterally from said pedestal and horizontally reciprocable thereon, manually operable means for moving the table, said means being mounted on the table, and a vertically disposed oscillating mechanism comprising a series of interconnected links movable as a unit in a vertical plane, said link mechanism being pivoted to the pedestal and table for supporting the offset outer side of the table throughout its movement in a straight line.

4. In a lining and beveling machine, a pedestal, a horizontally disposed rail secured thereon, a flat work table offset laterally from said pedestal and having its inner side mounted to reciprocate on said rail, manually operable means for moving the table, said means being mounted on the table, and a vertically disposed oscillating mechanism comprising a series of interconnected links movable as a unit in a vertical plane, said link mechanism being pivoted to the pedestal.

estal and table for supporting the offset outer side of the table throughout its movement in a straight line.

5. In a lining and beveling machine, a pedestal, a horizontally disposed rail thereon, a flat work table offset laterally from said pedestal and having its inner side mounted to reciprocate on said rail, manually operable means for moving the table, said means being mounted on the 10 table, and a vertically disposed oscillating mechanism comprising a series of interconnected links movable as a unit in a vertical plane, said mechanism having pivots fixed on the pedestal and a pivot on the table and movable therewith for 15 supporting the offset outer side of the table throughout its movement in a straight line.

6. In a lining and beveling machine, a pedestal, a horizontally disposed rail thereon, a flat work table offset laterally from said pedestal and having its inner side mounted to reciprocate on 20 said rail, manually operable means for moving the table, said means being mounted on the table, and a vertically disposed oscillating mech-

anism comprising a series of interconnected links movable as a unit in a vertical plane, said link mechanism having two pivots fixed on the pedestal forming the fulcrum for the centers of motion and a pivot on the table for supporting 5 the offset outer side of the table throughout its movement in a straight line.

7. In a lining and beveling machine, a pedestal, a horizontally disposed rail thereon, a flat work table offset laterally from said pedestal and 10 having its inner side mounted to reciprocate on said rail, manually operable means for moving the table, said means being mounted on the table, and a vertically disposed oscillating mechanism comprising a series of interconnected links 15 movable as a unit in a vertical plane, said link mechanism having fixed pivots disposed in vertical alinement on the pedestal forming the fulcrum for the centers of motion and a pivot on the table for supporting the offset outer side of 20 the table throughout its movement in a straight line.

VERNON E. ROYLE.
